PREPAYMENT MECHANISM FOR GAS METERS

Friedrich von Schütz, Berlin-Lichterfelde,
GermanyApplication August 7, 1933, Serial No. 684,051
In Germany August 12, 1932

4 Claims. (Cl. 194—90)

This invention relates to prepayment mechanisms used in connection with gas meters which mechanisms stop the supply of gas when the prepaid quantity has passed the meter.

5 In prepayment mechanisms of this type the element which actuates the valve for stopping the flow of gas is operated upon the insertion of coins into the prepayment mechanism in such a way that it opens the coin valve, whereas upon 10 the consumption of gas it is actuated in such a way that it will close this valve when the inserted coins have been used up. In the prepayment mechanisms as hitherto known this actuating element is upon the switching through 15 of each coin moved a certain distance in longitudinal direction in one sense. When gas is supplied this actuating element is moved in opposite direction and closes the coin valve while running through the last part of this backward way. In 20 order to have a sufficient passage for the gas when the coin valve is open the way travelled by the valve disk when same is lifted and closed must be large enough and as the valve should not close until the last prepaid coin is being used 25 up the distance travelled by the actuating element upon the insertion or consumption respectively of one coin cannot be chosen too small. On the other hand, if it should be possible to 30 prepay a rather large number of coins, the whole way travelled by the actuating element becomes very long and gives cause to rather large dimensions of the prepayment mechanism. It is an 35 object of this invention to provide a prepayment mechanism which in spite of having a large lifting way of the coin valve allows a sufficiently high number of coins to be prepaid without increasing the dimensions of the device.

Another object of this invention is to provide 40 a prepayment mechanism which is to be operated by two kinds of coins of different value and size, as f. i. shillings and pennies.

A further object of the invention is to provide 45 means for indicating the value of the inserted amount of money which has not yet been used up.

It is still a further object of the invention to provide a construction which is such that it is impossible to operate the coin mechanism in another way than with these coins and that it is 50 impossible to any unauthorized person to take the coin out of the prepayment mechanism again after same has been switched through.

According to this invention there is provided 55 a worm shiftable along its shaft and meshing with a worm wheel. Upon the insertion of a

coin of lower value the worm is turned by a certain angle and as the worm wheel is held fixedly in its position the worm is shifted along its shaft in one direction. Upon the insertion of a coin of high value the worm wheel is turned and thereby shifts the worm by one pitch in the same direction. When gas is supplied the worm wheel is turned by the counting mechanism of the gas meter in the direction opposite to that occasioned by the switching through of a coin 10 of lower value and, meshing with the worm wheel, moves in the opposite direction longitudinally on its shaft. Upon the last revolution in this direction the worm is coupled with the actuating element mounted rotary on the same 15 shaft and imparts a turning movement to same during the last part of its last revolution. This movement of the actuating element is transmitted to the coin valve, and serves for closing same. It will be seen from this that it is not the 20 last part of the longitudinal way of the worm which is utilized for actuating the valve but the last part of the last revolution of the worm. Thereby the way which has to be travelled by the actuating element upon closing or lifting 25 the coin valve is not limited to a fraction of one pitch of the worm as in the hitherto known prepayment mechanisms; the pitch of the worm therefore can be chosen small enough to ensure the possibility of storing a high number of coins 30 without being compelled to dimension the mechanism excessively large.

To the shaft of the worm two rotary movements in opposite directions have to be imparted, one upon the switching through of a 35 coin of lower value and one upon the consumption of gas. This is attained by means of a differential gear. The shafts of the planet-wheels of this gear are fixedly connected to the shaft of the worm and are driven in one 40 direction by one sun wheel actuated upon the insertion of a coin of lower value and in the opposite direction by the other sun wheel upon the consumption of gas. As the worm and the worm wheel act also like a differential gear, the 45 construction according to this invention contains two differential gears, which allows to impart three movements to the worm, i. e. one upon the insertion of a coin of lower value, one upon the insertion of a coin of high value and one upon the supply of gas, without these imparments interfering with each other even if they take place at the same time.

The accompanying drawings illustrate an embodiment of this invention in connection with 55

a dry gas meter of the known type with one diaphragm and two double seat valves which are reversed at the end of the strokes of the diaphragm. The prepayment mechanism shown there is adapted to be operated by shillings and pennies, whereby no restriction is made to the use of these coins, as the mechanism may just as well be designed for other kinds of coins.

In the drawings:

10 Fig. 1 is a front view of a gas meter provided with a prepayment mechanism according to this invention, the front plate being partly removed.

Fig. 2 is a sectional view taken along line AB of Fig. 1.

15 Fig. 3 is a back view of the gas meter partly in section, the back casing being removed entirely and the diaphragm being removed partly only.

Fig. 4 is a plan view of the prepayment device.

20 Fig. 5 is a detail of the prepayment device showing the actuation by a coin of high value and the means for indicating the amount of unused money.

25 Fig. 6 is a further detail showing the locking of the coin-slots after a coin has been inserted and is switched through.

Referring to the drawings, 1 represents the casing of the gas meter provided with the inlet connector 2 and the outlet connector 3. Inside 30 the casing there is a ring 4 to which the diaphragm 5 carrying the plate 6 is fastened. The diaphragm and the plate are guided in parallel fashion by the rods 7 and move to and fro when gas is passing the meter. Beneath the connector casings segment shaped chambers 8 and 9 are arranged each of them being provided with a double seated valve 10 and 11 respectively, which valves are reversed at the end of the strokes of the diaphragm in known manner by a suitable reversing mechanism, which, however, as it does not form part of the invention has been omitted from the drawing in order not to complicate same. Near the top of the casing the counting mechanism 12 is provided 35 in a gas tight box 13. This counting mechanism comprises a double pawl and ratchet drive 14 which in known way is actuated by a lever 15 fastened to the shaft 16 of the diaphragm guide lever 7.

50 Within the inlet connector 2, above the channel 20 connecting the connector with the valve housing 21, the seat 22 for the coin valve 23 is arranged. The valve disk 23 is by means of a ball and socket joint 24 connected to the lever 25 secured to the shaft 26. This shaft has its bearings in the walls of an indenture 27 of the casing 1 and carries inside the casing 1 the lever 28 provided with a pin 29. The lever 28 is actuated at its pin 29 by means of lever 30 secured to shaft 31. When moving in clockwise direction, the lever 30 closes the coin valve 23; whereas when the lever 30 is moving in the opposite direction the coin valve is opened by means of the spring 32 arranged on the shaft 26. The shaft 31 of the valve actuating lever 30 extends through the front wall of the casing 1 and is driven by the prepayment device which will be described in the following:

70 In front of the gas meter casing 1 a box 36 is arranged. In this box a horizontally disposed shaft 37 is provided in two suitable bearings 38. The shaft 37 is provided with a key 39. Shiftable along this shaft is a worm 40 carrying abutments 41 at one end by means of which the worm is coupled with the valve actuating

element 42 in its extreme right position, this element carrying corresponding abutments 43. The actuating element 42 mounted loosely on the shaft 37 is provided with an extension 44 which by means of the link 45 and the lever 46 is connected to the shaft 31 extending through the front wall of the casing 1 and serving for actuating the coin valve as described before.

10 On the shaft 37 a differential gear is arranged comprising two sun wheels 50 and 51 and two planet wheels 52 and 53. The hub 54 carrying the axes of the planet wheels is rigidly fastened to the shaft 37, whereas the sun wheels are running loosely on this shaft. The hub of the sun wheel 51 carries the worm wheel 55 meshing with the worm 56. By means of this worm and the train gear 57 arranged between this worm and the counting mechanism 12 the sun wheel 51 is driven. The other sun wheel 50 is provided with a ratchet toothed engaging with a corresponding toothed of the ratchet wheel 61. The hub of the ratchet wheel 61 has a lateral extension 62 which by means of link 63 is coupled to the coin operated lever 65.

15 Beneath the shaft 37 and perpendicular to it the shaft 66 is provided in suitable bearings 67 which shaft carries rigidly connected to it the worm wheel 68 engaging with the worm 40 and the ratchet wheel 69 actuated by the pawl 70 connected to the second coin operated lever 71.

20 Above the shaft 37 and perpendicularly to it the rotary coin receiver 74 is provided which outside the box 36 carries a knob 75 by means of which it is to be turned. The receiver is furnished with two slots 76 and 77 somewhat smaller than the respective coins. In the top wall of the box 36 two corresponding slots 78 and 79 for the insertion of the coins are provided. Two channels 80 and 81 serve for guiding the inserted coins into the slots of the coin receiver.

25 The coin operated levers 65 and 71 are mounted rotary on the axes 84 and are provided with contact surfaces 85 and 86. The lever 65 has an extension to the end of which the link 63 is hinged. To the lever 71 the pawl 70 is hinged at 88 which engages with the ratchet wheel 69. A spring 89 serves for keeping the pawl in position.

30 The operation of the device is the following. If a coin 90 of lower value is inserted it projects from the receiver 74. When same is turned in clockwise direction, the coin pushes the contact surface 85 aside and thereby the lever 65 is turned to such an extent that by means of the ratchet wheel 61, the ratchet toothed of the sun wheel 50, the planet wheels 53 and 54, and the shaft 37, the shaft 37 is turned 35 by 1/2 revolution. As the worm wheel 68 is held in its position by the pawl 70 engaging with the ratchet wheel 69, the worm 40 to which this turning movement is imparted by the key 39 is shifted to the left.

35 If a coin 91 of higher value is inserted and switched through it will engage with the contact surface 86 thus causing the lever 71 to deflect. By means of the pawl 70, the ratchet wheel 69, and the worm wheel 68, the worm is shifted by one pitch along the shaft 37.

40 When gas is supplied the counting mechanism 12 driven by the to and fro going diaphragm 5, by means of the train gearing 57, the worm 56 and the worm wheel 55, drives the sun wheel 55.

51. This sun wheel imparts by means of the planet wheels 53 and 54 a rotary movement to the shaft 37 which movement is opposite to the one imparted to it when a coin of lower 5 value is switched through. By this rotary movement the worm 40 is shifted along the shaft 37 to the right. When all the inserted coins except one coin of lower value have been used up the abutments 41 of the worm 40 come into contact with the abutments 43 of the actuating element 42 and upon the consumption of the gas corresponding to the value of this last coin the worm 40 will turn this actuating element which by means of its extension 44, link 45 and lever 15 46, turns the shaft 39 which serves for actuating the coin valve 23. If a coin of lower value is now inserted the worm 40 will turn backward and if a coin of higher value is inserted it will move to the left and in both cases the worm 20 wheel releases the actuating element 42 which allows the coin valve 23 to open under the influence of its spring 32.

For indicating the value of the inserted amount of money which has not yet been used up, a strip 93 carrying numbers is arranged near the front of the box 36 shiftable in bearings 25 94. By means of a lateral extension 95 engaging with a groove 96 this strip is coupled to the worm 40. Furthermore a shaft 97 carrying a disk 98 is provided which shaft is coupled to the shaft 37 of the worm 40 by means of a bevel gear system 99, 100. The disk 98 is provided with numbers 0, 1, 2 . . . 11 and also with a helical window 101 through which one 30 35 of the numbers on the strip 93 can be seen. A window 102 in the front plate permits to read the numbers on the strip 93 representing the still available amount of full shillings, whilst the numbers on the disk 98 representing the still available amount of pence are to be recognized through the window 103. The helical window 101 serves for covering the numbers on the strip 93 which are adjacent to the one indicating the true number of full shillings so that 40 45 only one number is to be seen behind the window 102 in spite of the strip 93 being moved continuously upon the insertion of pennies.

In order to prevent the coin operated levers 65 and 71 from being actuated in a fraudulent 50 way by wire hooks or the like, a screen 105 is provided between the insertion slots 78 and 79 in the top wall of the box 36 and the channels 80 and 81 for leading the coins into the slots 76 and 77 of the coin receiver 74. This screen rests 55 on the heads of two pins 106 attached to the top wall of the box 36 and is provided with two slots 107 which allow a diagonal movement of the screen. The coin operated levers 65 and 71 are provided each with extensions 108 and 109 by means of which the screen 105 is shifted 60 diagonally upon the switching through of a coin. In case someone should try to actuate the coin operated levers by a wire hook or the like introduced through the slots 78 or 79, the screen can 65 not be shifted and thereby locks the coin operated levers 65 and 71.

The screen 105 is provided with an extension 111 projecting downward by means of which the screen is shifted to lock the coin slots when the 70 worm 40 is brought into its extreme left hand position in order to prevent the insertion of more money.

When a coin is switched through the device it drops into the receptacle 112 as soon as it comes 75 out of contact with one of the surfaces 85 or 86

respectively. When the coin receiver is turning back under the influence of the spring 113 the coins are stripped off by the arms of the coin operated levers carrying the contact surfaces 85 and 86 and thereby it becomes impossible to 5 take the coin out again after same has been switched through f. i. by means of a thread fastened to the coin.

When returning to its initial position the coin receiver 74 actuates by means of stop 114 the 10 angle lever 115 which serves for pushing back the screen 105 by means of its downward projecting extension 116 and thereby the coin slots 78 and 79 are unlocked again.

I claim:

1. A prepayment mechanism for gas meters comprising a shaft, a worm movable lengthwise on the shaft to and from an initial position of prepayment and rotating with said shaft, a worm wheel engaging the worm and operative 20 to move the same lengthwise on said shaft, a differential gear consisting of two sun wheels running loosely on said shaft and two planet wheels provided with axes rigidly connected to said shaft, with one sun wheel having a driving 25 connection with the gas meter to rotate the shaft and the worm thereon, the rotation of the worm against the thrust of the engaged worm wheel operating to move the worm on the shaft away from its initial position, a coin operated 30 lever and mechanism actuated thereby to turn the other sun wheel to rotate the shaft in the opposite direction to move the worm toward its initial prepayment position on the shaft, a second coin operated lever and a pawl and ratchet 35 mechanism operated by said lever to rotate said worm wheel to move the worm toward its initial prepayment position, a rotary coin receiver having two slots for receiving coins of different size and value and operating to move the coins into 40 engagement with the respective coin operated levers to actuate the latter as the receiver is rotated, an actuating element on said shaft, means for coupling said actuating element with said worm when the latter is moved to its extreme position away from its initial prepayment position on said shaft, a gas controlling 45 valve, and mechanism operated by said actuating element for controlling the operation of the valve. 50

2. A prepayment mechanism for gas meters comprising a shaft, a worm movable lengthwise on the shaft to and from an initial position of prepayment and rotating with said shaft, a worm wheel engaging the worm and operative 55 to move the same lengthwise on said shaft, a ratchet wheel coupled to said worm wheel, a differential gear consisting of two sun wheels running loosely on said shaft and two planet wheels provided with axes rigidly connected to said shaft, with one sun wheel having driving 60 connections with the gas meter to rotate the shaft and the worm thereon, the rotation of the worm against the thrust of the engaged worm wheel operating to move the worm on the shaft away from its initial position of prepayment, a coin operated lever and mechanism actuated thereby to turn the other sun wheel to rotate the shaft in the opposite direction to 65 move the worm toward its initial prepayment position on the shaft, a second coin operated lever, a spring pressed pawl hinged to said second coin operated lever and engaging said ratchet wheel so that actuation of the lever rotates the ratchet 70 75

- wheel and the coupled worm wheel to move the worm toward its initial prepayment position on the shaft, a rotary coin receiver having two slots for receiving coins of different size and value and operative to move the coins into engagement with the respective coin operative levers, an actuating element on said shaft, means for coupling said actuating element with the said worm when the latter is moved to its extreme position away from its initial prepayment position on said shaft, a gas controlling valve, and mechanism operated by said actuating element for controlling the operation of the valve.

3. A prepayment mechanism for gas meters comprising a shaft, a worm movable lengthwise on the shaft to and from an initial position of prepayment and rotating with said shaft, a worm wheel engaging the worm and operative to move said worm lengthwise on said shaft, a differential gear consisting of two sun wheels running loosely on said shaft and two planet wheels provided with axes rigidly connected to said shaft, with one sun wheel having a driving connection with the gas meter to rotate the shaft and the worm thereon, the rotation of the worm against the thrust of the worm wheel operating to move the worm on the shaft away from its initial position of prepayment, a coin operated lever and mechanism actuated thereby to turn the other sun wheel to rotate the shaft in the opposite direction to move the worm toward its initial position of prepayment, a second coin operated lever and a pawl and ratchet mechanism operated by said lever to rotate said worm wheel to move the worm toward its initial prepayment position, a rotary coin receiver having two slots for receiving coins of different size and value and operative to move the coins into engagement with the respective coin operative levers, an actuating element on said shaft, means for coupling said actuating element with the said worm when the latter is moved to its extreme position away from its initial prepayment position on said shaft, a gas controlling valve, mechanism operated by said actuating element for controlling the operation of the valve, and a shiftable screen for closing the coin-receiving slots in the rotary receiver, said screens being actuated by the coin operated levers.

4. A prepayment mechanism for gas meters comprising a shaft, a worm movable lengthwise on the shaft to and from an initial position of prepayment and rotating with said shaft, a worm wheel engaging the worm and operative to move the same lengthwise on said shaft, a differential gear consisting of two sun wheels running loosely on said shaft and two planet wheels provided with axes rigidly connected to said shaft, with one sun wheel having a driving connection with the gas meter to rotate the shaft and the worm thereon, the rotation of the worm against the thrust of the engaged worm wheel operating to move the worm on the shaft away from its initial position, a coin operated lever and mechanism actuated thereby to turn the other sun wheel to rotate the shaft in the opposite direction to move the worm toward its initial prepayment on the shaft, a second coin operated lever and a pawl and ratchet mechanism operated by said lever to rotate said worm wheel to move the worm toward its initial prepayment position, a rotary coin receiver having two slots for receiving coins of different size and value and operative to move the coins into engagement with the respective coin operative levers, an actuating element on said shaft, means for coupling said actuating element with the said worm when the latter is moved to its extreme position away from its initial position on said shaft, a controlling valve, mechanism operated by said actuating element for controlling the operation of the valve, and a shiftable screen for closing the coin-receiving slots in the rotary receiver, said screens being actuated by the coin operated levers.

FRIEDRICH VON SCHÜTZ
